ALFRED D. KARR, OF NEWARK, NEW JERSEY, AND KARL D. PERKINS, OF NEW YORK, N. Y., ASSIGNORS TO AUDIFFREN REFRIGERATING MACHINE CO., OF NEW YORK, N. Y., A CORPORATION OF NEW JERSEY.

REFRIGERATING MACHINE.

Application filed March 3, 1922. Serial No. 540,802.

To all whom it may concern:

Be it known that we, ALFRED D. KARR and KARL D. PERKINS, both citizens of the United States, and residing, respectively, at Newark, county of Essex, and State of New Jersey, and New York, county and State of New York, have invented certain new and useful Improvements in Refrigerating Machines; and we do hereby declare the following to be a full, clear, and exact description of the invention, such as will enable others skilled in the art to which it appertains to make and use the same.

Our invention is directed to improvements in refrigerating machines, and is particularly applicable to refrigerating machines of the Audiffren type, i. e. self-contained hermetically sealed refrigerating machines in which a refrigerant is continuously circulated from the compressor end where it is compressed, cooled and liquefied, to the cold or expansion end where it expands, vaporizes, abstracts heat from the surrounding cold brine or atmosphere and is returned by suction to the compressor.

The working parts of such machines are respectively connected with the container or shell of the machine which is rotated from without, and with a weighted mass within the container, the gravity effect of which opposes the force of compression. Such machines, as customarily designed, are inherently protected against generating excessive pressures because of the fact that, upon the occurrence of any unusual pressure or temperature conditions tending to unduly increase the work of compression, the forces of compression overcome the gravity opposition of the weight and the weighted mass revolves with the container, thereby putting an end to the compression, which can not be resumed until after the machine is brought to rest. When the weighted mass has once been thrown over the top center it quickly attains the speed of the shell, and its continued rotation under the driving force intended, in normal operation, to rotate the shell and move the working parts against the resistance of compression, now imposes severe stresses on the moving parts and causes undue wear.

The primary object of this invention is to provide means acting automatically to

restrain the compressing operation within predetermined limits and by thus unloading the machine to prevent the rotation of the weighted mass. In the preferred embodiment of the invention hereinafter described in detail, its object is effected by putting in the suction line of the compressors a valve which is automatically actuated, whenever the weighted mass moves through an excessive angle from its normal position of rest, to reduce the volume of gas flowing into the compression cylinders and thereby reduce the resistance to compression.

Inasmuch as machines of the type in question are completely sealed there is no way of knowing, at any particular time, what degree of inclination the weighted mass has assumed, or whether it is rotating with the shell. By means of the indicator mechanism hereinafter described we have been able to determine and indicate the actual movements of the weighted mass and it is observed that, whereas when the machine is running under normal conditions the weighted mass will stand at a fairly constant angle, when the resistance to compression becomes excessive the weighted mass will begin to oscillate with a progressive pendulum action which finally culminates, unless conditions change, in the rotation of the weighted mass with the shell. By observing the conditions of operation of given machines under varying conditions, making use of the indicating device referred to, we have been able to determine what is the best angle of inclination for the weighted mass, and to design the machines and the automatic unloading device accordingly. With this device we are also able to determine whether a machine which has been in service for a long period is functioning normally, without returning the machine to the factory and opening the hermetically sealed bells.

In the drawings;

Figure 1 is a section on the line 1—1 of Figure 2.

Figure 2 is an enlarged section taken substantially on the line 2—2 of Figure 1.

Figure 3 is a radial section showing an alternate construction,

Figure 4 is a section at right angles to Figure 3,

Figure 5 is a view similar to Figure 4 in another plane,

Figure 6 is a view similar to Figure 4 of an alternate construction.

- 5 The improved machine comprises condensing and refrigerating tanks 1 and 2, in which are arranged the condenser 6 and the expansion member 7, respectively, the said members being secured to a hollow shaft 10 70
 10 3 journaled in bearings 4. The condenser 6 is a sectional spherical casing having axial bearings 13 threadedly engaging the shaft and the sections having a tongue and groove connection as indicated at 14. The weighted 15 member 5 is in the form of a casting, having hubs journaled on the shaft 3, and supports compressor cylinders 8. The pistons 9 of the cylinders are connected by rods 11 with straps 12 on an eccentric 10 secured 20 to the shaft 3, so that when the shaft is rotated with respect to the casting the pistons will be reciprocated. 25

The compressor draws the gas from the expansion member 7 through the hollow 25 shaft 3, and discharges the gas through valve controlled discharge ports 15 into the condenser 6. Within the condenser, the refrigerant is cooled and liquefied by contact with the walls of the same, which are 30 in turn cooled by the condensing water in the tank 1. The condensed refrigerant and the oil are thrown out and held against the wall of the condenser, and are caught by a scoop on the casting, and passed down into 35 a separating cup 16 forming a part of the casting 5. Here the oil and the refrigerant separate by gravity, the oil flowing back onto the parts to lubricate the same, while the refrigerant flows by way of a pipe 17 40 into a float chamber 18. This chamber has an outlet port to a pipe 19 held axially of the hollow shaft 3, and the port is controlled by a float operated valve 20, the float being operated by the liquid in the tank 18, when 45 it reaches a predetermined level, to open the valve, to permit the refrigerant to flow through the pipe 19 to the expansion member 7.

The compressor, constituted by the cylinders and pistons draws the gaseous refrigerant from the expansion member through the hollow shaft 3, by way of a passage 21 leading radially from the hollow shaft. A valve chamber 22 is arranged adjacent to 50 the passage 21, and communicates with the said passage, and the valve chamber also communicates with a passage 23 which branches to inlet ports 24 of the respective cylinders. These ports are controlled by 55 the rocking of the cylinders, each cylinder having journal pins 25, journaled in bearings 26 in the counter-weighted casting. 60

In the valve chamber 22, we arrange a valve 27, in the present instance a ball 65 valve, which is controlled by gravity, to-

ward and from its seat 28. The axis of the valve chamber 22 is inclined with respect to the vertical, at a selected angle, so that under normal working conditions, the valve will of its own weight roll away from the seat, leaving the communication free between the compressor and the expansion member. When however, because of reaction to the compressing force, the axis of the valve passes beyond a selected angle the valve will roll toward its seat, and will close or partially close the communication between the compressor and the expansion chamber, thereby reducing the work of compression. A by-pass 29 is provided around the valve, to prevent complete occlusion of the communication, although if desired this by-pass may be omitted so that the valve will cut off entirely the admission of gas to the cylinders from the expansion chamber. 80 85

It has been found by the indicating mechanism to be later described, that under normal conditions, the counter-weighted casting rides steadily at a relatively low angle, even with comparatively high operating temperature, seldom exceeding a mean of 25° from its rest position. With increasing pressure, there occurs an accelerated swinging of the casting. That is, any increase of load, instead of gradually raising the counter-weight, starts it to swinging, and if the increase of load is more rapid than the tendency of the counter-weight to come to rest, the amplitude of the swing will increase continuously. The casting swings as a pendulum, to an equal degree above and below the neutral point corresponding to the steady running position for the load being carried, and it will not swing over, to revolve with the compression member unless the casting reaches in its swing, an angle of 50° or 60°. The valve is extremely sensitive, and when the angle of the axis of the valve chamber passes the horizontal, the ball rolls instantly to its seat. 95 100 105 110

In practice we have preferred so to proportion the weight of the ball, the area of the suction intake and the size of the by-pass that when the ball has once seated, it will remain seated until the machine is brought to rest. Until the machine is stopped and the valve unseated, the compression and the refrigerating capacity of the machine is reduced by an amount depending upon the design of the parts, and particularly upon the dimensions of the by-pass. Obviously, it is possible to so proportion the weight of the ball, the size of the intake orifice and the size of the by-pass, that the ball will roll off its seat when the weighted mass swings below the horizontal. In such case the effect will be to reduce the volume of gas drawn into the compression cylinders and, if the abnormal conditions 115 120 125 130

are not too extreme or too long continued, relief will be attained without discontinuing the compressing operation, while the abnormal conditions persist.

- 5 It will be obvious that any mechanism which will automatically reduce the suction, when the counter-weighted casting passes beyond a selected angle will answer the purpose and may if desired, use a plurality 10 of valves, so arranged that they will seat at different angles. In Figures 3 to 5 inclusive, there is shown a construction wherein a plurality of valves is provided. In this arrangement, the port 30 from the hollow 15 shaft communicates with two chambers 31 and 32, each carrying a ball valve 33. The axes of the chambers are arranged at different angles, so that the valves will seat successively, one seating at a selected angle, 20 while the other seats at a larger angle. The first valve to seat will reduce the suction to a certain degree, and it will be later reduced further by the seating of the second valve.

In Figure 6 there is shown a construction 25 wherein a valve is provided for controlling the communication with each cylinder. Ports 34 and 34' lead from the passage 35 corresponding to the passage 21 of Figure 2 to the several cylinders, and each of these 30 ports is controlled by a valve arranged within a chamber 36 and 37, respectively. The axes of these chambers are arranged at different angles, so that the valves will seat in succession, one valve closing the communication with one cylinder, and the other closing the communication with the other cylinder. In either of the constructions 35 last described, by-passes may be provided if desired.

- 40 When a machine is completed, and charged and sealed, since the operating parts are hidden, it is practically impossible under normal conditions to determine the conduct of such parts during operation, and 45 in Figure 1 we show mechanism for permitting the relative position of the parts during operation, to be observed. The said mechanism comprises a cored shaft 38, which is adapted to be inserted axially of 50 the hollow shaft 3. This shaft 38 has its inner end tapered as shown at 39 and the nut 40 which seals the adjacent end of the suction passage has a tapered recess to receive the tapered end of the shaft 38. By 55 inserting the shaft 38, and pressing the tapered end firmly into the recess of the nut 40, the shaft 38 will be connected to the counter-weighted casting, to move therewith. A packing nut 41 encircles the shaft 60 38 at the outer end of the hollow shaft 3, and a pressure gauge 42 of usual construction is connected with the outer end of the shaft 38. An indicator 43 extends radially from the shaft near the pressure gauge, and 65 this indicator cooperates with a scale 44 ad-

jacent to the indicator. The bore of the shaft 38 has lateral ports, communicating with the interior of the compression member 6, so that the pressure in such member is indicated by the gauge.

The above described mechanism is especially designed for shop testing of the machine, and is used in the following manner. After the machine has been charged and sealed in the usual manner, it is operated 70 until the brine in the tank 2 is reduced to a temperature of 14° F., corresponding to the boiling point of sulfur-dioxide vapor at atmospheric pressure. Under these conditions that part of the refrigerant which is not liquefied will exist at atmospheric pressure in both the expansion and condenser members. The sealing plug in the outer end of the shaft 3 may then be removed substantially without the escape of refrigerant. 75 The shaft 38 is then inserted and the packing 80 41, which has threaded engagement with the shaft 3, is screwed firmly into place, driving the tapered tip of the shaft 38 into the tapered recess of the plug 40. 85 When the parts are tight, the machine may be operated in the usual manner, and the indicator 43 will indicate the exact position of the counter-weighted casting in the machine. Any changes in the position of the casting, through the time of operation of the machine, will be indicated by change in the position of the indicator with respect to the scale. This information is supplemented by the reading of the pressure gauge 90 which gives the pressure within the condenser. 95

The operation of the machine as a whole is as follows: Under normal conditions the compressor sucks gas from the cold end and compresses it and delivers it into the inside of the shell at the condenser end where it is liquefied, collected, separated from the oil, and passed back into the cold end to expand. 100 If the resistance to compression tends to increase too rapidly or to exceed the gravity effect of the weighted mass, that mass will begin to oscillate and when it swings too high the valve will seat, reducing the suction 105 passages and thereby the volume of gas drawn into the compressing cylinders thus reducing the resistance to compression, and the tendency of the weighted mass to oscillate. The volume of gaseous refrigerant flowing between the expansion chamber and the compressing cylinders is thus reduced during the incipient or initial stages of the movement of the weighted mass embodying the compressing cylinders and before it begins to rotate with the compression chamber. 110 If the parts are so designed that the ball valve remains on its seat, the refrigerating effect will be reduced by a fixed amount until the machine is brought to rest and restarted. 115 If the parts are so designed that 120 this indicator cooperates with a scale 125 130

- the ball valve is alternately seated and unseated, the compression will be reduced by this intermittent reduction of the gas flow, and if normal conditions are restored before 5 the weighted mass turns over, the machine will resume operation at normal capacity. Where a plurality of valves are used, as above suggested, it is possible to so design them that one or more will remain seated 10 and another or others will roll off from their seats on the back swings of the weighted mass. In such cases an intermediate effect is possible, as will be understood.
- While the indicating mechanism is designed primarily for shop use, it is obvious that it may be made a permanent part of the machine, furnishing thus a means of determining at any time the operation of the machine.
- 20 What we claim is:
1. In a refrigerating machine, including an expansion member and a rotating compression member connected therewith, a compressor within the compression member and operated by the relative movement of the compression member with respect thereto, said compressor being free to move with the compression member under excessive pressure whereby to stop the compressing 25 operation, and means controlled by the movement of the compressor beyond a selected angle for reducing the volume of gaseous refrigerant admitted to the compressor, thereby to permit the parts to function without increasing the compression.
  2. In a refrigerating machine, including an expansion member and a rotating compression member connected therewith, a compressor within the compression member 30 and operated by the relative movement of the compression member with respect thereto, said compressor being free to move with the compression member under excessive pressure whereby to stop the compressing operation, and means controlled by the movement of the compressor beyond a selected angle, for instantly reducing to a predetermined fixed value, when said angle is reached, the rate of transfer of gas to the 35 compression member.
  3. In a refrigerating machine, including an expansion member and a rotating compression member connected therewith, a compressor within the compression member 40 and operated by the relative movement of the compression member with respect thereto, said compressor being free to move with the compression member under excessive pressure whereby to stop the compressing operation, and means controlled by the movement of the compressor beyond a selected angle, for instantly reducing to a predetermined fixed value, when said angle is reached, the rate of transfer of gas to the 45 compression member.
  4. In a refrigerating machine, including an expansion member and a rotating compression member connected therewith, a compressor within the compression member and operated by the relative movement of the compression member with respect thereto, said compressor being free to move with the compression member when the pressure exceeds a selected means whereby to stop the compressing operation, and means controlled by the movement of the compressor beyond a selected angle for reducing the suction between the compressor and the expansion member, said means comprising a gravity operated valve for closing the communication between said members and arranged to seat when the compressor moves to the selected angle, and a by-pass arranged around the valve.
  5. In a refrigerating machine, including an expansion member and a rotating compression member connected therewith, a compressor within the compression member and operated by the relative movement of the compression member with respect thereto, 50 said compressor being free to move with the compression member when the pressure exceeds a selected mean whereby to stop the compressing operation, and means controlled by the movement of the compressor beyond a selected angle for reducing the suction between the compressor and the expansion member, said means comprising a ball valve for closing the communication between said members and mounted to roll toward and 55 from its seat on a track inclined at an angle such that when the compressor moves to the selected angle the ball will roll to its seat, a by-pass being provided around the valve.
  6. A refrigerating machine comprising an expansion member and a rotary condensing member connected therewith, said rotary condensing member comprising, two members mounted to rotate one within the other, and operated by the relative movement of the said members, the inner member constituting a compressor and the outer member forming a compression chamber and a cover for the inner member, said inner member being mounted to rotate with the outer member to stop compression when the pressure in the outer member becomes excessive, and means controlled by the movement of the inner member with the outer member beyond a selected angle for instantly reducing to a predetermined fixed value, when said angle is reached, the volume of gas flowing to the compression member.
  7. A refrigerating machine having an expansion member and a rotatable condensing member connected therewith including rotatably mounted inner and outer members operated to compress by the relative movement of the members, the outer member enclosing the inner member and forming a compres- 125

sion chamber, and means outside the compression chamber for indicating the position and movement of the inner member.

8. A refrigerating machine having an expansion member and a rotatable condensing member connected therewith including rotatably mounted inner and outer members operated to compress by the relative movement of the members, the outer member enclosing the inner member and forming a compression chamber, and indicating mechanism for indicating the position and movement of the inner member and having means for connection with said inner member.
15. 9. A refrigerating machine having an expansion member and a rotatable condensing member connected therewith including rotatably mounted inner and outer members operated to compress by the relative movement of the members, the outer member enclosing the inner member and forming a compression chamber, indicating mechanism for indicating the position and movement of the inner member and having means for connection with said inner member, said indicating mechanism comprising a hollow shaft having an indicator, and a fixed scale with which the indicator cooperates, the bore of the shaft communicating with the compression chamber, and said shaft carrying a pressure gauge for the purpose specified.

10. Refrigerating mechanism, comprising communicating expansion and compression chambers, and a refrigerant therein, the compression chamber being mounted to rotate, compressing mechanism within the same and operated by the relative movement of said mechanism and the compression chamber, said mechanism being arranged to rotate with the compression chamber under excessive pressure, and means for restricting the volume of gaseous refrigerant flowing between the expansion chamber and

the compressing mechanism said means being controlled by the incipient movement of the compressing mechanism with the compression chamber, thereby to prevent the rotation of the compressing mechanism with the compression chamber.

11. Refrigerating mechanism, comprising communicating expansion and compression chambers, the compression chamber being mounted to rotate, compressing mechanism within the same and operated by the relative movement of said mechanism and the compression chamber, said mechanism being arranged to rotate with the compression chamber when the pressure exceeds a predetermined mean, and means for restricting the communication between the expansion chamber and the compressing mechanism controlled by the incipient movement of the compressing mechanism with the compression chamber, said means comprising a gravity operated valve, and a track along which the valve moves to its seat, when the track is inclined beyond a selected angle.

12. In a refrigerating machine including an expansion member and a rotating compression member connected therewith, a compressor within the compression member and operated by the relative movement of the compression member with respect thereto, said compressor being free to move with the compression member when the pressure therein becomes excessive whereby to stop the compressing operation, and means controlled by the movement of the compressor beyond a selected angle for reducing in predetermined steps the volume of gas flowing between the expansion member and the compressor.

In testimony whereof we affix our signatures.
